UNITED STATES PATENT OFFICE

THOMAS G. PARADINE, OF ERIE, PENNSYLVANIA.

STOP-COCK BOX.

997,412.

Specification of Letters Patent. Patented July 11, 1911.

Application filed July 11, 1910. Serial No. 571,385.

To all whom it may concern:

Be it known that I, THOMAS G. PARADINE, a citizen of the United States, residing at Erie, in the county of Erie and State of Pennsylvania, have invented certain new and useful Improvements in Stop-Cock Boxes; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

This invention relates to improvements in metallic casings for stop-cocks which are used to control the flow of water or gas from the main into the service pipes of a building, and which are usually located outside of the building and at varying depths beneath the surface of the ground or pavement, rendering it necessary to have some means for permitting ready access to the stop-cock or valve to turn the same.

The present invention has for its object to provide a metallic casing in telescoping sections and to provide in the telescope joint between the two sections means whereby the upper section of pipe will be retained in such extended position as may be desired without the use of external means for that purpose. These and other features of my invention will appear hereinafter in the specification and claims and are illustrated in the accompanying drawings in which:

Figure 1, is a view in elevation of my improved stop-cock box a part thereof being broken away. Fig. 2, is a transverse section of the same on the line $x-x$ in Fig. 1, looking downward. Fig. 3, is a like view on the line $y-y$, looking downward.

In these drawings, A, indicates the lower section of my improved stop-cock box, and B, indicates the upper tubular section of the same which is adapted to telescope into the lower section A, as shown in Fig. 1. C, indicates the valve-stem which is adapted to engage a valve in a service pipe, (not shown) in the usual manner. The upper end of the pipe, B, is closed with a closure plate, D, all of which parts are of usual and ordinary construction, except as hereinafter noted and explained.

In setting stop-cock boxes, as usually constructed, the upper section, B, thereof will not stay in an extended position so that the

earth may be filled in around it to the proper level, unless a prop of some kind is placed between the bottom of the trench and the cap D, and when such a prop is used it is very difficult if not impossible to remove it after the trench is filled up. For the purpose of causing the upper section of the stop-cock box to remain in an extended position I make an annular groove, a , in the upper end 65 of the lower section, A, in which groove I place a spring ring, E, which is adapted to grip the upper section or pipe, B, with sufficient force to sustain the weight thereof, and thereby prevent the same from sliding downward in the lower section, A, of the stop-cock box. This spring ring, E, is preferably formed of brass, but any metal which will not be destroyed by rust or corrosion may be employed.

To prevent the upper section, B, from turning in the lower section, A, when it is desired to remove or replace the cap, D, thereon, I provide within the lower section, A, splines or ribs, a' , and the lower end of the 80 tube, B, is split and flattened sufficiently to form projecting lips, b , which engage the sides of said splines, a' and prevent the tube, B, from turning in the lower section, A, of the stop-cock box.

When my improved stop-cock box is being placed in position for use, the workman has only to place the lower end thereof over the stop-cock, connect the stem, C, to the valve then raise the tube, B, up far enough so that 90 the cap, D, will be at the level of the ground or pavement, at which elevation the spring ring, E, will retain it while the workmen are filling in the trench.

Having thus described and illustrated my 95 invention so as to enable others to construct and use the same, what I desire to secure by Letters Patent is:

1. The combination in a stop-cock box of lower and upper telescopic sections of tubing, a friction ring embracing and automatically clamping the upper section, and means to prevent said ring from moving downward below the upper end of the lower section, substantially as set forth.

2. The combination in a stop-cock box of a lower tubular section, having an annular groove around the upper end of the tubular cavity in said lower section, a metallic spring ring in said annular groove, and an upper 110 section of tubing inserted telescopically within said lower section so that the same will

be embraced and automatically clamped by the spring ring in said annular groove, substantially as and for the purpose set forth.

3. The combination in a stop-cock box, of a lower tubular casing having an annular groove around the upper end of the tubular cavity therein, longitudinal splines within said cavity, an upper tubular section having its lower end split and flattened so as to engage the sides of said splines extending through said lower tubular section, a closure

cap on the upper end thereof, and a spring ring within said annular groove embracing said upper tubular section substantially as set forth.

15

In testimony whereof I affix my signature, in presence of two witnesses.

THOMAS G. PARADINE.
